UNITED STATES PATENT OFFICE

2,662,504

PENCIL SHARPENER

Otto Schneider, Cincinnati, Ohio

Application July 3, 1952, Serial No. 297,068

4 Claims. (Cl. 120—89)

1

This invention relates to pencil pointers. An object of this invention is to provide an improved sharpener for pencils employed by draftsmen, designers, engineers, architects and students who require a sharp-pointed pencil in their work. The pencil sharpener commonly used consists of a paddle having sheets of sandpaper or abrasive glued to the opposite faces thereof. Such sharpeners will sharpen the lead of a pencil, but the graphite that accumulates on the sandpaper is a source of dirt and smudge, and this dirt and smudge gets onto the drawings no matter how great care is taken to avoid it.

An object of this invention is to provide a sharpener in which the abrasive is housed within a compartment and which is provided with means for removing loose particles of graphite from the pencil before it is withdrawn from the sharpener.

A further object of the invention is to provide a sharpener in which the abrasive is in the form of a belt which can be advanced with use to provide clean abrasive as and when needed, and which is also provided with means for brushing the graphite particles from the abrasive and collecting it in the housing.

A still further object of the invention is to provide a pencil sharpener of the type referred to above that is light in weight and inexpensive to manufacture.

Other objects of the invention will in part be apparent and will in part be obvious from the following description taken in conjunction with the accompanying drawings in which:

Figure 1 is a top plan view of a pencil sharpener embodying a form of the invention;

Fig. 2 is a view in section taken on line II—II of Fig. 1;

Fig. 3 is a view in section taken on line III—III of Fig. 1; and

Fig. 4 is a view in perspective of the abrasive belt support embodied in the sharpener in the preceding view.

In Fig. 1 of the drawings is illustrated a sharpener 1 comprising a box-like housing having a bottom section 2, and a cover 3. An abrasive belt 4 is housed in section 2. The belt 4 is supported at its forward end on a hollow mandrel 5, and at the rear on a roller 6. The roller 6 is supported from mandrel 5 by means of pins 7 that extend into the hollow of the mandrel through openings 7' in the rear wall 8 thereof. The openings as shown are adjacent the ends of roller 6. The outer end of each pin is formed with an eye or loop 9 in which are journaled stub shafts 10 and 11 secured to the ends of roller 6. Shaft 11 ex-

2

tends through a vertical slot 11' in the end wall 12 of box section 2, while shaft 10 terminates short of the adjacent end wall 13. A knob 14 is secured to the shaft 11 for turning roller 6 and the abrasive belt.

In order that belt 4 may be held taut compression coil springs 15 are provided. As shown pins 7 extend into these springs. Pins 7 are provided with cross pins 16 which bear against the rear ends of the springs. When the pins 7 are pushed into the mandrel springs 15 are compressed between the front wall of the mandrel and the cross pins 16.

When roller 6 is inserted through belt 4, the springs compressed and the stub shafts are mounted in the ends of the roller and the eyes of pins 7, the belt is held taut.

The mandrel 5 is an elongated member, the length of which is approximately equal to the length of section 2. The ends of mandrel 5 are provided with tongues 18 and 19 that are received in notches 20 in the top of the end walls of section 2.

The mandrel 5, roller 6 and belt 4 together with the belt tightening means, may be assembled as a unit, and can, therefore, be mounted in place in box section 2 or be removed therefrom as a unit.

As may be seen in Fig. 3, the forward or front side of the cover 3 has an opening 21. This opening 21 extends the full length of the cover so that the entire length of the abrasive belt may be used for sharpening or pointing pencils.

At the right-hand end of the belt, as shown in Fig. 2, there is provided a section of fabric 22 in the form of velvet or similar material upon which the lead of the pencil may be rubbed after sharpening to remove loose particles of graphite. In order to keep the surface of the abrasive belt 4 clean, including the surface of the fabric section 22, a brush 25 is provided. Brush 25 is disposed of the underside of the abrasive belt and engages it near the forward end thereof. The brush extends the full length of the abrasive and fabric portions of the belt and is supported by a wire frame 26, the ends of which are curled to form spring sections 27. The free ends of the spring sections 27 are anchored in bosses 28 and the ends of box section 2 as shown in Fig. 2.

The cover 3 is so constructed as indicated in Fig. 3 that it may be easily removed or secured in place. The rear edge of the box section 2 is provided with a flange 30 having a slot 31 therein that receives a flange 32 formed along the bottom of the rear side of the cover. The front corners of cover 3 are provided with lugs 33 adapted to

register with lock shoulders 34 at the corners of box section 2, as shown. Thus, when the cover is mounted in place as shown in Figs. 1, 2 and 3, the flange 32 is locked in the slot 31, and the bosses 33 are nested in the sockets 34.

The box section 2 may be made from suitable plastic which can be conveniently molded to the desired shape. Cover 3 may be made of clear transparent plastic so that the sharpening operation may be observed.

The pencil sharpener as illustrated and described may be mounted or placed on a draftsman's table at any convenient place for him. To sharpen the point of a pencil, the pencil point is inserted into the opening from the front of the 15 cover, and rubbed on the surface of the abrasive belt. When the point has been sharpened to the desired degree, the loose particles of graphite are removed by stroking it on the fabric section 22. The graphite as removed in the sharpening process is collected and stored in the box. The loose graphite cannot be picked up by the hands or blown around in the air by currents of air to be deposited on drawings and other surfaces which are so difficult to keep clean. Therefore, the 20 sharpener embodying my invention has many self-evident advantages over the commonly used sandpaper sharpeners. The graphite removed in the sharpening process accumulates in the box. To remove it, all one needs to do is to remove the 25 cover and the belt and either wash the graphite out or empty it in an envelope which can be sealed and destroyed.

Having thus described the invention what is claimed as new and desired to be secured by 35 Letters Patent is:

1. A pencil sharpener comprising a housing having a box-like bottom and a cover, the housing having an opening in one side thereof for accommodating the end of a pencil, a roller in the hous- 40

ing adjacent a sidewall opposite said opening, a mandrel mounted in said housing parallel to said roller and disposed adjacent to the sidewall containing said opening, means for rotatably supporting the roller from the mandrel, and an endless belt having an abrasive coating thereon, said belt being trained over said mandrel and roller, the mandrel serving as a backing member for the belt when a pencil inserted through said opening is being sharpened on the belt.

10 2. A pencil sharpener according to claim 1 characterized by the fact that means are provided for yieldingly urging the roller in a direction to tighten said belt.

20 3. A pencil sharpener according to claim 1 characterized by the fact that a brush is disposed within the housing on the underside of said belt and mounted to engage the belt to remove graphite therefrom as the belt is advanced by said roller.

25 4. A pencil sharpener according to claim 1 characterized by the fact that the brush is co-extensive with the length of the belt, and that means are provided for yieldingly urging the brush against said belt.

OTTO SCHNEIDER.
